Specification of Letters Patent. Patented Aug. 31, 1915.

Application filed March 9, 1914. Serial No. 823,549.

To all whom it may concern:

Be it known that we, ABNER F. CONNER and GUY L. WILLETT, citizens of the United States, and residents of Indianapolis, county 5 of Marion and State of Indiana, have invented a certain new and useful Sign; and we do hereby declare that the following is a full, clear, and exact description thereof, reference being had to the accompanying 10 drawings, in which like letters refer to like parts.

The object of this invention is to improve the formation of letters for signs and the like, particularly with reference to the shading 15 of said letters.

One feature of the invention consists in providing a hollow letter-shaped frame, open at the front, so that lamps can be placed within said letters, and means for 20 indicating the proper shading for such letter. The means herein shown for indicating such shading consists in painting the outer surfaces at one side of said letter and also the adjacent background of a certain suitable 25 color for indicating shading, and also placing electric lamps on said background adjacent such shaded sides, said lamps being colored to correspond with the color of the painted surfaces.

30 The nature of the invention will be understood from the accompanying drawings and the following description and claims.

In the drawings, Figure 1 is a front elevation of a portion of a sign showing one letter thereof. Fig. 2 is a section on the line 35 2-2 of Fig. 1.

In the drawings there is shown in detail a plate 10 on which the letters constituting the sign are secured, and it constitutes the 40 background for the letters. To said plate metal or like plates 11 are secured, forming the outline of the letter throughout. There is shown herein the letter "R", although the invention is not limited to any particular 45 letter or other design. In Fig. 2 the two parallel plates 11 are shown as formed by one sheet of metal, which is bent U-shaped with a bottom secured to the background plate 10, but this arrangement is immaterial. The letter proper, therefore, is hollow 50 and opens outwardly as shown. Within the hollow letter incandescent lamps 12 are secured. They may be any desired color but ordinarily are unpainted. The shading in 55 the letter "R" as indicated in Fig. 1, is to

the left of the letter surfaces or plates 11. Therefore the outer surfaces of the left-hand plates 11 all the way around the letter are painted with some color, say, dark green. Likewise, a portion 13 of the background plate 10 adjacent the painted portions of the outer walls of the letter 11 are painted the same color to a width corresponding to the usual width of shade lines for lettering. Incandescent lamps 14 are 60 secured to the painted portion of the background plate 10 and near the shaded side walls of the letter 11, and said lamps 14 are colored to agree with the color of the paint, say, dark green. In order to give the proper 65 perfection of shading, angle plates 15 are secured to the background plate 10 at the ends of the painted surfaces 13 of the plate 10 so as to conceal the lamps 14 from the unshaded side of the letter. Hence the 70 right-hand side surfaces of the letter "R" are unshaded and the left-hand side surfaces are all shaded. The result of this arrangement is to produce a beautiful shaded 75 letter effect and with the proper coloring of 80 surfaces and lamps an unusually beautiful sign is produced, and it is not only a well shaded letter after dark when illuminated, but it appears to be equally well shaded in the day time because of the painted surfaces. 85

The invention claimed is:

1. A sign including a back-ground plate, a hollow open-front letter or design carried by said plate and with its side walls projecting therefrom at substantially right 90 angles, illuminating means within said letter or design, colored lamps adjacent the outer side surfaces of said letter or design facing in one general direction adapted to represent shading, and plates to cut off the light of the 95 adjacent colored lamps from the non-shaded sides of the letter.

2. A sign consisting of a back-ground plate, a hollow open-front letter or design carried by said plate and having its side walls projecting therefrom at substantially right angles, illuminating means in the recess of said design or letter, and shading formed by painting the outer side surfaces of said design or letter facing in one general 100 direction and the adjacent portions of the back-ground plate the desired shading color.

3. A sign consisting of a back-ground plate, a hollow open-front letter carried by said plate and having its side walls project- 110

ing therefrom at substantially right angles, illuminating means in the hollow portions of said design or letter, shading formed by painting the outer side surfaces of said design or letter facing in one general direction and the adjacent portions of the back-ground plate the desired shading color, and lamps on said shaded portions having the same color as the shaded portions.

10 4. A sign consisting of a back-ground plate, a hollow open-front letter carried by said plate and having its side walls projecting therefrom at substantially right angles, uncolored incandescent lamps in the hollow portions of said design or letter, the outer side surfaces of said design or letter and adjacent surfaces of the back-ground in one

general direction being painted a desired shading color, incandescent lamps secured to the back-ground plate in the shaded portion thereof and colored like the shading color, and plates extending from the corners of said design or letter adapted to cut off the light of the adjacent colored lamps from the non-shaded sides of the letter. 20 25

In witness whereof, we have hereunto affixed our signatures in the presence of the witnesses herein named.

ABNER F. CONNER.
GUY L. WILLETT.
